UNITED STATES PATENT OFFICE.

MAXIMILIAN J. OTTO, OF NEW YORK, N. Y.

SPOOL-HOLDER.

1,137,079.

Specification of Letters Patent. Patented Apr. 27, 1915.

Application filed July 26, 1913. Serial No. 781,296.

To all whom it may concern:

Be it known that I, MAXIMILIAN J. OTTO, a citizen of the United States, residing in the borough of Manhattan, city, county, 5 and State of New York, have invented a new and useful Improvement in Spool-Holders, of which the following is a description.

This invention relates to spool-holders 10 and particularly to spool-holders adapted to be applied to sewing-machines.

Among the objects of my invention may be noted the following: to provide means, for holding a spool upon the arm of a sewing-machine, which may be readily removed and quickly applied, and which may be applied to any type of sewing-machine now known to me; to provide a spool-holder for sewing-machines for holding spools of 20 thread thereon in position for supplying thread to the needle or other executive element of the machine, and by means of which the thread may be freely paid off from the spool without fear of entanglement with the spool or spool-holding means; to provide a simple, cheap and effective spool-holding device having frictional means for holding it to the ordinary spool-spindle, or similar support, of the 25 machine, and capable of being raised and lowered on said spindle, or adjusted, or rotated thereon for purposes presently described; to provide a spool-holder made of a single piece of resilient material; and to 30 provide a spool-holder which may be adapted to or substituted for the ordinary spool-holder now found on domestic and manufacturing machines.

With the above objects in view and others 40 which will be detailed during the course of this description, my invention consists in the parts, features and elements, and combinations thereof hereinafter described and claimed.

In order that my invention may be clearly understood, I have provided drawings wherein: Figure 1 is a side elevation of a portion of a sewing-machine showing the application of my invention; Fig. 2 is a 45 perspective view of my spool-holder; Fig. 3 is a top-plan view showing my spool-holder in place on a portion of the machine, the spool being shown in dotted outline; and Fig. 4 is a view similar to Fig. 3 but 50 showing the parts in a different position.

Referring to the drawings, it will be seen

that my spool-holder, in the form which I have chosen to illustrate for the purposes of this application, consists of a single piece of material. Preferably, I form the spool-holder from resilient wire capable, when bent into the form of my invention, of applying friction to the spindle or pin to which it is adapted.

Referring to Figs. 1 and 2, it will be seen 65 that my spool-holder consists of a securing portion and a spool-holding portion. The securing portion comprises a loop or eye 1 formed at one end of the wire and adapted to slide freely over the spindle 2, usually 70 extending vertically from the sewing-machine arm 3. A portion 4 extends from the eye which is bent obliquely upward and substantially reversely to form the V-shaped resilient or spring tongue 5 located mid- 75 way, or substantially so, between the eye 1 and a similar oppositely disposed eye 6, formed in the wire, the material of the wire being extended beyond the spring tongue and bent to form said eye 6 and the member 80 7 of the securing portion. Beyond the eye 6, the wire is extended at an angle as at 8, and then at a right-angle as at 9, to form the spool-holding portion, and then extended parallel with the member 8, to form the 85 spool-holding pin 10. The distance between the spool-holding pin 10 and the securing portion is sufficient to afford space for the largest spool that may be used on any sewing-machine, domestic or manufacturing. 90

In the several figures it will be seen that the two eyes 1 and 6 are arranged in alignment, or so that they have the same, or substantially the same, center. It will also be seen that the spring-tongue is arranged between the two eyes and directly in line, or substantially so, with the centers thereof, so as to press with considerable force or friction upon the spindle 2, to which the holder is applied. Thus, when the securing 100 portion is slipped down over the spindle 2, the latter passes through both the eyes 1 and 6, and the tongue, between the two eyes, frictionally engages the said spindle. The friction between the tongue and the spindle 105 retains the spool-holder firmly upon the spindle, but permits its easy removal and rotation on the spindle. The frictional hold of the tongue also permits the spool-holder to be adjusted on the spindle so as to locate the free end of the spool-holding pin 110 10 as far as may be desired from the base

of the spool or the arm 2 of the machine; but, it should be understood that the arrangement of the pin 10 is such that its free end will be a distance above the base, or eye 1, of the securing portion of the spool-holder. Thus, when the spool is set upon the machine arm with the spindle 10 extending into the axial passage thereof, the spool will be so held as to prevent the thread, 10 should it freely unwind and become loose about the bottom of the spool and rest upon the arm, from becoming knotted, entangled, or otherwise impeded in its free passage to the executive elements of the machine.

15 To apply a spool to the holder, it is only necessary, after having placed the holder in position as shown in Fig. 1, to rotate the holder upon the spindle 2 until the spool-holding pin 10 is beyond the machine-arm 20 sufficiently far to permit the spool 11 to be slid thereon, as shown in Fig. 4. Then the spool-holder is rotated, by pressure upon the spool, back to the position shown in Figs. 1 and 3, so that the spool may rest on the 25 machine-arm. It will also be understood that a fresh spool of thread may be quickly applied and that any size spool can be accommodated.

In some instances the spool-spindle 2, 30 found on a manufacturing machine, may not be adapted to receive my holder, in which event a spindle, such as 2, may be substituted for such special spool-spindle.

Having thus described my invention, what 35 I claim and desire to secure by Letters Patent is:

1. A spool-holder comprising a pair of eyes arranged in alinement and adapted to

loosely engage a supporting pin; and a spring tongue arranged intermediate said 40 eyes and extending into the space between them for frictionally retaining the holder in desired position on said supporting pin.

2. A spool-holder formed of a single piece of resilient wire and bent to provide a 45 spool-holding pin and a securing portion, the latter comprising a holding-eye for loosely engaging a supporting pin, and a tongue extending across said eye and adapted to frictionally engage said supporting 50 pin.

3. A spool-holder having a spool-pin, an eye for loosely encircling a supporting-pin, and a resilient tongue for frictionally engaging said supporting pin, whereby the 55 spool-pin may be adjusted relatively to the supporting pin.

4. A spool-holder formed of a single piece of resilient wire bent into substantially **U** 60 form, and having at one end a spool-holding pin and at its other end a securing portion consisting of a pair of spaced apart eyes adapted for loosely engaging a supporting-pin, and an intermediate spring tongue extending into the space between the 65 eyes so as to frictionally engage the supporting-pin passing through said eyes, whereby to adjustably and firmly secure the spool-holder upon said supporting-pin.

In testimony whereof I have hereunto signed my name in the presence of two sub- 70 scribing witnesses.

MAXIMILIAN J. OTTO.
